UNITED STATES PATENT OFFICE.

GEORGE W. PRESSELL, OF PHILADELPHIA, PENNSYLVANIA, ASSIGNOR TO E. F. HOUGHTON & COMPANY, OF PHILADELPHIA, PENNSYLVANIA, A CORPORATION OF PENNSYLVANIA.

MATERIAL FOR CARBURIZING.

No Drawing.

Application filed March 25, 1922. Serial No. 546,807.

To all whom it may concern:

Be it known that I, GEORGE W. PRESSELL, a citizen of the United States, residing in Philadelphia, Pennsylvania, have invented

Material for Carburizing, of which the following is a specification.

One object of this invention is to provide a carburizing material for use in case hardening; which in addition to being of relatively low cost and economical to use, shall be highly efficient; the invention contemplating a material of such a nature as will insure the production of uniformly hardened articles free from soft spots.

Another object of the invention is to provide a carburizing material of such a nature as shall permit of its use with a relatively inexpensive filler for the carburizing pots.

I also desire to provide a novel method of applying a carburizing material to objects to be case hardened, as well as a novel method of case hardening which shall be convenient, inexpensive and easy to operate.

In carrying out my invention I prepare my carburizing material in the form of a paste with which the steel to be hardened may be coated or into which the steel objects may be dipped. Said paste consists essentially of carbon dust, energizers such as nitrogenous products either with or without any or all of the carbonates of barium, sodium and calcium, with a binder such as molasses, sulphite liquor, or other organic carbonaceous liquid. As typical of such nitrogenous products I may use cyanides, cyanimides, etc.

The mixture of the above ingredients in accordance with my invention has a pasty consistency while retaining certain of its liquid qualities and after the objects to be hardened have had this material applied in the form of a coating, as above noted, by brushing, dipping or otherwise, they are placed in a carburizing pot upon a bed of carbon dust or pulverized coke. The spaces within or surrounding the coated steel objects are now filled with coke or other relatively inexpensive carbonaceous material and a cover is applied to the pot, which is luted in the customary manner. The pot with its contents is placed in a carburizing furnace and exposed to a temperature of between 1600° and 1750° F. for a length of

time dependent upon the depth of case hardening desired.

Under these conditions the articles are hardened with the utmost certainty and uniformity inasmuch as the paste coating of carbon and energizers is in direct contact with the steel and being in a substantially uniform layer thereon, as well as at a substantially uniform distance from all parts of the surface, results in a perfectly uniform, satisfactory product.

It is particularly to be noted that both the material described and the process of using it are relatively inexpensive and convenient, for all of such material applied to the steel objects is actually utilized in the hardening process and the space within the pot surrounding said objects is filled with inert material of relatively low value. There is thus none of the uneven or uncertain action which has hitherto characterized case hardening processes involving the repeated use of carburizing material which has been to a greater or less extent exhausted and which has become contaminated with iron scale or fire clay.

Since the filling material used may be absolutely inert or may consist of coke which is used merely as a carbonaceous filler, the process depends solely upon the carburizing action of the paste or coating applied to the articles to be case hardened. Obviously the proportions in which the ingredients of the paste are used may be widely varied to suit different conditions without departing from my invention, although I find that the standard proportions commonly employed in solid carbonaceous carburizing mixtures will give satisfactory results.

If desired, and without departing from my invention, I may omit the inert or other packing, merely coating the objects to be case hardened and heating them to the required temperature in a closed pot.

I claim:

1. A carburizing material of pasty consistency consisting of a liquid vehicle, carbon and at least one carbonate.
2. A carburizing material in the form of a paste consisting of a carbonaceous liquid vehicle, carbon and an energizing material including at least one carbonate.
3. A carburizing material in the form of

a paste consisting of a carbonaceous liquid vehicle, carbon and an energizing material including a nitrogenous substance and at least one carbonate.

5. A carburizing material in the form of a paste consisting of a carbonaceous liquid vehicle, carbon and an energizing material

including at least one carbonate and a nitrogenous material.

5. A carburizing material in the form of a paste consisting of a carbonaceous liquid vehicle, carbon and a plurality of metallic carbonates.

GEORGE W. PRESSEILL
